CLAIM

The ornamental design for a lamp, as shown and described.

DESCRIPTION

1. Lamp
2. Lamp
5. Lamp
- 1.1: Perspective
- 1.2: Perspective
- 1.3: Front
- 1.4: Back
- 1.5: Left
- 1.6: Right
- 1.7: Top
- 1.8: Bottom
- 2.1: Perspective
- 2.2: Perspective
- 2.3: Front
- 2.4: Back
- 2.5: Left
- 2.6: Right
- 2.7: Top
- 2.8: Bottom
- 5.1: Perspective
- 5.2: Perspective
- 5.3: Front
- 5.4: Back
- 5.5: Left
- 5.6: Right
- 5.7: Top
- 5.8: Bottom

(Continued)

The broken lines shown in the drawings are included for the purpose of illustrating portions of the lamp that form no part of the claimed design.

1 Claim, 24 Drawing Sheets
